RAILWAY SWITCH OPERATING APPARATUS

Herbert L. Bone, Forest Hills, Pa., assignor to The Union Switch & Signal Company, Swissvale, Pa., a corporation of Pennsylvania

Application June 22, 1939, Serial No. 280,600

4 Claims. (Cl. 246—319)

My invention relates to railway switch operating apparatus, and particularly to apparatus of the type which includes a facing point lock the locking plunger of which is automatically operated to unlock the switch when a train trails the switch by means mechanically actuated by the train.

One object of my invention is to provide, in apparatus of the type described, an electrically operated means for positively preventing operation of the locking plunger for any reason, as for example, by dragging equipment, during facing point moves over the switch.

Other objects and characteristic features of my invention will become apparent as the description proceeds.

My present invention is an improvement on the apparatus described and claimed in Letters Patent of the United States No. 1,976,827, granted to me on October 16, 1934, for Railway switch operating apparatus.

I shall describe one form of apparatus embodying my invention, and shall then point out the novel features thereof in claims.

In the accompanying drawings, Fig. 1 is a top plan view showing a spring switch A controlled by a switch operating mechanism B constructed in accordance with my invention. Fig. 2 is an enlarged top plan view of the switch operating mechanism B shown in Fig. 1 with the circuit controller and the main cover removed to better illustrate the novel portion of the mechanism. Fig. 3 is a longitudinal sectional view of the mechanism shown in Fig. 2. Fig. 4 is a detail sectional view taken substantially on the line IV—IV of Fig. 3. Fig. 5 is a detail view of electric lock mechanism forming part of the switch operating mechanism illustrated in the preceding views, and embodying my present invention.

Similar reference characters refer to similar parts in each of the several views.

Referring first to Fig. 1, the reference character A designates a railway switch comprising, as usual, two fixed rails 1 and 1a and two movable rails 2 and 2a. The fixed rails 1 and 1a are laid on tie plates 3 and are secured to cross ties 4 in the usual manner. The movable rails 2 and 2a are fastened together by a front rod 5, a head rod 6, a bridle rod 7, and a tie rod 8, and may be moved into a normal or a reverse position by means of a switch operating mechanism B which is connected with the head rod 6 through the medium of an operating rod 9 and a spring connecting rod C. When the switch occupies its normal position in which position it is shown

in Fig. 1, the movable rail 2 engages the fixed rail 1, and the movable rail 2a is spaced a slight distance from the fixed rail 1a. When the switch is reversed, however, the movable rail 2a then engages the fixed rail 1a and the movable rail 2 is spaced from the fixed rail 1.

The spring connecting rod C may have any desired construction, but as here illustrated, it is similar in all respects to that described in my prior patent referred to hereinbefore. It is believed, therefore, that for purposes of my present invention it is sufficient to point out that this connecting rod includes spring means which biases the switch points to whichever extreme position they are moved to by the mechanism B with sufficient force to permit facing point moves over the switch without displacement of the points, but which yields when a train trails the switch and thereby allows the train to force the switch points to a position opposite to that to which they are biased by the spring means.

The switch operating mechanism B is mounted on one end of a tie strap 10 which is secured to the ties adjacent the outer side of the rail 1, and, as best seen in Figs. 2 and 3, this mechanism, in the form here shown, comprises a main casing 11 provided at its left-hand end with a tail-like projection 11a to which an auxiliary casing housing a circuit controller E (see Fig. 1) is secured. The upper end of the main casing 11 is closed by a cover 12 which is secured to the casing by means of studs 12a, as shown in Fig. 3.

The circuit controller E forms no part of my present invention and may, for example, be similar to the circuit controller E shown and described in my prior patent referred to hereinbefore. Inasmuch as this circuit controller forms no part of my present invention, it is believed to be unnecessary to describe it further herein.

Formed in the main casing 11 is an axially extending rectangular guideway 13 which slidably receives a motion plate 14. The motion plate 14 is provided on its upper face with rack teeth 15, and on its lower face with a cam slot 16, and is adapted to be reciprocated between two extreme positions by means of a hand-throw lever 17 fixed to a shaft 18. The shaft 18 is journaled in suitable bearings 19 secured to the casing 11, and has fixed thereto a segment gear 20 which meshes with the rack teeth 15. As best seen in Fig. 2, the cam slot 16 is formed with a portion at each end which is parallel to the direction of movement of the motion plate, and with an intermediate connecting portion 55 which is disposed at an angle to the direction

of movement of the motion plate. Extending into the cam slot 16 and cooperating therewith is a roller 21 which is mounted on a pin 22 secured to an arm 23 forming part of a crank 24. The crank 24 is journaled in a vertical bearing 25 provided in the bottom of the casing 11 and has fixed thereto on the underside of the casing a removable switch operating arm 26 which is pivotally attached to the free end of the operating rod 9.

Reciprocably mounted in the casing 11 directly above the motion plate 14 is a locking device 27 comprising two spaced parallel side members 27a and 27b connected together at their opposite ends by means of integral end members 27c and 27d. The left-hand end member 27c carries a rectangular locking plunger 27e, and is formed with two spaced threaded holes 27f and 27g, while the other end member 27d is provided with three unthreaded holes 27h, 27i and 27k, two of which holes, 27h and 27k align, respectively, with the threaded holes 27f and 27g. The locking plunger 27e projects with some clearance into a longitudinally extending rectangular slot 28 provided in the tail-like projection 11a of the casing 11, and cooperates at its inner end with a lock rod L which is slidably mounted in a transverse slot 29 formed in the tail-like projection 11a. The lock rod L, in the form here shown, is of standard construction, and comprises two longitudinally adjustable bars 30 and 31 attached at one end to the front rod 5 of the switch A, and provided with registering notches 32 so disposed that these notches will align with the locking plunger 27e when and only when the switch A occupies the extreme position in which it is shown in Fig. 1. The locking device 27 also comprises two bolt members 27l and 27m which pass through the holes 27h and 27k, respectively, and are screwed into the threaded holes 27f and 27g. These bolt members also extend with some clearance through holes 33 and 34 formed in lugs 35 and 36 secured to the upper face of the motion plate 14, and surrounding each bolt member between the associated lug 35 or 36 and the end member 27d is a compressed coil spring 27n which biases the locking device 27 in the direction to cause the locking plunger 27e to enter the notches 32 in the lock rod L.

Vertical displacement of the locking device 27 and the motion plate 14 are prevented by a hold-down member 40 (see Fig. 4) which hold-down member is formed integrally with a casting 41 which is bolted at one end to the opposite sides of the casing 11 by means of bolts 42, and at the other end to the casing by means of the previously referred to studs 12a. The hold-down member 40 is provided on its underside near its opposite ends with hold-down surfaces 40a and 40b which are adapted to slidably engage the upper edges of the side members 27a and 27b, respectively, of the locking device 27.

For reasons which are clearly explained in my prior patent referred to hereinbefore, the parts of the locking device 27 are so proportioned that when the motion plate 14 is in its left-hand or normal extreme position, as shown in Figs. 2 and 3, the biasing springs 27n will tend to drive the locking device to an extreme position which is beyond the desired locking position. The locking device is prevented from moving beyond the desired locking position, under these conditions, however, by linkage which connects the locking device with the tie rod 8. As here shown, this linkage includes a plunger bolt 50 which extends

5 with some clearance through the hole 27j in the end member 27d, and the head of which bolt engages the left-hand side of the end member 27d as viewed in Figs. 2 and 3. The threaded end of plunger bolt 50 is adjustably connected by means of a turnbuckle 51 (see Fig. 1) with one end of a link 52, the opposite end of which is pivotally connected with the long arm 53a of a bell crank lever 53. The bell crank lever 53 is pivotally supported in a crank stand 54, and has its short arm 53b pivotally connected with one end of an operating rod 55. The other end of the operating rod 55 is connected with the previously described tie rod 8 by means of a standard switch basket 56. The tie rod 8 may be located at any suitable location, but will preferably be located approximately halfway between the heel and the point of the switch. The base of the crank stand 54 is secured both to a gauge plate 57 and to the tie strap 10 upon which the mechanism B is mounted, and it will be apparent, therefore, that any loss of adjustment between the parts due to creepage of the ties is prevented. The plunger bolt 50, turnbuckle 51, link 52, bell crank lever 53, operating rod 55, spring basket 56, and tie rod 8 also constitute means for effecting unlocking of the switch points during a trailing move, as will be made clear presently.

30 The operation, as a whole, of the portion of the apparatus thus far described is as follows: When the hand-throw lever 17 occupies the extreme position in which it is shown in full lines in Figs. 1 and 2, the motion plate 14 is held in its extreme left-hand or normal position as viewed in Figs. 2 and 3, and the roller 21 on crank 24 is held at the extreme end of its stroke in a clockwise direction, as viewed in Figs. 1 and 2. When the crank 24 occupies this extreme position, a force is exerted on the movable rails 2 and 2a of the switch through the medium of the operating rod 9, the spring connecting rod C, and the head rod 6, which force holds the movable rails in their normal extreme positions in which they are shown in Fig. 1. When the movable rails are in their normal positions, the notches 32 in the lock rod L align with the locking plunger 27e, and the locking device 27 is therefore moved by the biasing springs 27n to its locking position in which the locking plunger partly enters the registering notches 32, thus securely locking the switch points in their normal positions.

50 When it is desired to reverse the switch, the hand-throw lever 17 is rotated from the extreme position in which it is shown in full lines in Fig. 1, to its opposite extreme or dotted line position. This movement of the lever causes the motion plate 14 to move from its extreme left-hand position as viewed in Figs. 2 and 3, to its extreme right-hand position. As soon as the motion plate has moved a short distance, the lugs 35 and 36 carried thereby engage the left-hand side of the end member 27d of the locking device 27, and as a result, as the motion plate continues to move, the locking device is moved with the motion plate, thus withdrawing the locking plunger from engagement with the notches 32 in the lock rod L, and hence unlocking the movable rails 2 and 2a. The parts are so proportioned that while the locking plunger 27e is being withdrawn from engagement with the notches 32 in the lock rod, the cam slot 16 in the motion plate will continue to engage the roller 21 on the crank 24 at that portion of the slot at its right-hand end which is parallel to the direction of movement of the motion plate, and as long as this

portion of the slot is engaging the roller, the crank 24 will remain stationary. It follows, therefore, that during that portion of the movement of the motion plate which is necessary to unlock the movable rails of the switch, no force is exerted on these rails tending to reverse them. As soon, however, as this first part of the movement of the motion plate has been completed, the roller 21 is then engaged by the curved portion of the cam slot 16 which causes the crank 24 to be rotated in a counterclockwise direction, as viewed in Fig. 2, and as a result, the movable rails are then moved to their reverse positions. It should be noted that as long as the movable rails remain stationary, the plunger bolt 50 remains fixed, so that during the first part of the movement of the motion plate, the end member 27d of the locking device 27 will move out of engagement with the head of the plunger bolt. As soon as the movable rails have started to move, however, the resultant movement of the tie rod 8 acting through the switch basket 56, operating rod 55, bell crank lever 53, and link 52 causes the plunger bolt to move in the same direction as the motion plate is moving, although the time of motion and the rate of motion of the plunger bolt will bear no direct relation to the movement of the motion plate. During the final movement of the motion plate, the portion of the cam slot 16 in the motion plate at the left-hand end of the slot which is parallel to the direction of movement of the motion plate engages the roller 21, which prevents further rotation of the crank 24, thus locking the movable rails in their reverse positions.

In order to restore the movable rails to their normal positions after they have been reversed as above described, the lever 17 is restored to the position in which it is shown in full lines in the drawings. The subsequent movements of the parts under these conditions are just the reverse of those described above, and it is believed, therefore, that the operation of the apparatus under these conditions will be readily understood from an inspection of the drawings without further description.

I shall now assume that the parts are in their normal positions, as shown in the drawings, and that a train trails the switch. As the leading wheels of the train roll along the fixed rail 1 and the movable rail 2a, the movable rails 2 and 2a are forced over laterally, but, before a sufficient force is developed to overcome the opposing force of the spring of the spring connecting rod C and cause the point of the movable rail 2 to move out of engagement with the fixed rail 1, the movable rails being somewhat resilient become bent, so that, with the usual standard split switch, the tie rod 8 is moved upwardly, as viewed in Fig. 1, three-quarters of an inch or more. This movement of the tie rod acting through the switch basket 56, operating rod 55, bell crank lever 53, link 52, and plunger bolt 50 moves the locking device 27 in opposition to the bias of the springs 27n a sufficient amount to withdraw the locking plunger 27e completely out of engagement with the notches 32 in the lock rod L, thus unlocking the switch. As a result, when the leading wheels have reached the positions in which a sufficient force is developed to cause the point of the movable rail 2 to move out of engagement with the fixed rail 1, the switch points will be unlocked, and the points will therefore be forced open by the wheels in exactly the

same manner as would be the case if no point lock were provided.

When the train which is trailing the switch has completely passed the switch, the movable rails will return to their normal positions under the bias of the spring connecting rod C. During this return movement of the movable rails there will be no deflection of these rails, and the locking plunger 27e will be moved into engagement with the lock rod L before the movable rails have reached their full normal positions in which the lock rod is in the proper position for the notches 32 therein to receive the locking plunger 27e. The springs 27n will therefore become compressed, and will urge the locking plunger 27e into engagement with the side of the lock rod, until the notches 32 move into alignment with the locking plunger, at which time the energy stored in the compressed springs 27n will force the locking plunger into place in the notches, thus restoring the switch to its normal locked condition. If the notches 32 in the lock rod L should not come into alignment with the locking plunger, a suitable indication of this fact will be given by means of the circuit controller E referred to hereinbefore.

During a facing point move there is no lateral thrust on the movable rails corresponding to, or commensurate with, that which occurs during a trailing movement, and what lateral thrust there is will be in the direction to permit the springs 27n to force the locking plunger further into the notches 32 in the lock rod L.

With the apparatus constructed in the manner thus far described it might possibly happen that when a train passes over the switch in a facing point direction a piece of dragging equipment would hook onto the tie rod 8 or the connecting rod 55, and would thus bend these parts out of shape to thereby actuate the linkage which connects the tie rod 8 with the locking device 27 to cause the locking plunger 27e to become withdrawn from the notches 32 in the lock rod L and thus unlock the switch. In order to prevent the possibility of such a condition from occurring I provide auxiliary electric lock mechanism which is effective when deenergized to lock the locking device 27 in the position in which it is shown in the drawings.

As here shown, this auxiliary locking mechanism comprises a locking dog 60 which is pivotally attached at its upper end to one end of a lever 61, and which cooperates at its lower end with a notch 62 provided in the upper side of an extension 63 formed on the end member 27d of the locking device 27. The lower end of the dog 60 also cooperates with two other notches 64 and 65 which are formed in the frame 41 on opposite sides of the notch 62, and which align laterally with the notch 62 when the locking device 27 occupies its locking position in which the locking plunger 27e is within the notches 32 in the lock rod L, but not when the locking device 27 is moved to its unlocking position in which the locking plunger 27e is withdrawn from the notches 32 in the lock rod L.

The extension 63 is slidably supported at its forward end within a guideway 48 formed in the hold-down member 40.

The dog 60 further cooperates with a depressor 66 which is pivotally supported on a pin 166 mounted in a pair of upstanding arms 61 provided on the frame 41, and which extends at one end between upstanding arms which are formed on the locking dog 60. The other end of the

depressor cooperates with a cam 68 formed on the extension 63 in such manner that when the locking device occupies its proper locking position, the dog will be prevented by the depressor from being raised far enough to withdraw it from the aligned notches 62, 64 and 65.

In order to permit the dog to be withdrawn when it is desired to unlock the switch in the intended manner, the notch 62 is made longer than the width of the dog, and the parts are so proportioned that the end 66b of the dog which cooperates with the cam 68 will ride off of the cam before the dog moves into engagement with the left-hand end of the notch, as will be made clear presently.

Formed on the depressor is a stop finger 66a which cooperates with a stop 67a provided on the arm 67 to limit the position to which the dog is free to rotate when it rides off of the cam 68.

The lever 61 is pivotally attached intermediate its ends to a fulcrum block 70 which is mounted for vertical sliding movement within a guideway 71 provided in a cross member 72 formed on the frame 41. The portion of the block which extends through the guideway 71 is round, and in order to prevent it from turning and still permit the desired vertical movement of the block, the block is pierced by a cotter key 13 the ends of which extend with clearance into vertical slots 14 provided in the opposite side walls of the guideway.

The fulcrum block 70 normally occupies a lowermost position in which it is shown in Fig. 3, and in which its lower end rests on the upper side of the cross member 21d of the locking device 27, but is arranged to be forced upwardly to a raised position in which it rides on top of the extension 63 at one side of the cam 68 when the locking device 27 is moved away from its locking position, and in order to facilitate moving the fulcrum block to its raised position in response to the movement of the locking device to its unlocking position, the fulcrum block and the extension are provided with inclined surfaces 70a and 63a, respectively.

The end of the lever 61 opposite to the locking dog 60 is bifurcated, and is operatively connected with the armature 75 of an electromagnet M by means of pins 76 which are secured to the sides of the armature at diametrically opposite points, and which extend with clearance into aligned vertical slots 77 provided in the ends of the bifurcations. The armature 75 is biased by means of a spring member 78 to a released position, and the parts are so proportioned that when the dog 60 is within the notches 62, 64 and 65 and the fulcrum block 70 is resting on top of the end member 21d, the armature will be free to move, by virtue of the slots 77, between its released and attracted positions without causing movement of the lever 61.

The magnet M is secured at its lower end to the frame 41, and is adapted to be energized when a train trails the switch by track circuits or their equivalent associated with the switch. These track circuits form no part of my present invention and are therefore not shown in the drawings. These track circuits may, for example, be similar to the track circuits shown in Letters Patent of the United States No. 1,606,455, granted to Frederick C. Stuart on November 9, 1926, in which event the magnet M may be controlled in the same manner as the magnet 38 shown in Fig. 8 of said patent.

Attached to the armature is an insulating strip

79 provided on its underside with a metal contact member 80 which, when the armature moves to its lowermost position, bridges two contact fingers 81 and 82 to form a contact 80-81-82. The contact fingers 80 and 81 are secured at the ends opposite to the bridging member 80 to an insulating block 83 provided on the frame 41. The contact 80-81-82 may be used to control a signal located at the switch, or for any other desired purpose.

The locking member further comprises a flat spring 84 which is secured to the lever 61 adjacent to the locking plunger 60, and which is provided at its free end with a return bend 84a, the lower leg of which cooperates with a pin 85 provided on the segment gear 20.

The operation of the mechanism as a whole is as follows: When the switch occupies its normal position in which it is shown in Fig. 1, and is locked in this position by the locking device 27, and the magnet M is deenergized, as will be the case if no train is then approaching the switch in either direction, or if a train is approaching the switch or passing over the switch in a facing point direction, the lever 61 will rotate by gravity to the position in which the dog 60 enters the aligned notches 62, 64 and 65. As was pointed out hereinbefore, when the dog is within the notches 62, 64 and 65, the locking device 27 is prevented from moving to the right far enough to unlock the switch, and it will be seen, therefore, that the auxiliary locking mechanism provides a means for preventing the switch from becoming unlocked under these conditions for any reason, due, for example, to dragging equipment hooking onto the lock releasing linkage. It will also be seen that, when the switch is locked in its normal position by the locking device 27, and the magnet M is deenergized, if the lever 61 should fail to rotate due to its gravity bias to the position in which the dog 61 enters the notches 62, 64 and 65, the cam 68 will engage the depressor 66 and will rotate it to a position in which it will force the dog downwardly to its proper position. Furthermore, if when the dog is within the notches 62, 64 and 65, the locking plunger 27 should be moved in the direction to unlock the switch far enough to raise fulcrum block 70, the dog will then remain in the notches 62, 64 and 65 due to its gravity bias.

When the parts are in the positions in which they are shown in the drawings and a train trails the switch, the resultant movement of the lock releasing linkage which takes place due to the lateral movement of the rails by the wheels of the train will cause the fulcrum block 70 to be raised and will also cause the depressor to ride off of the cam 68. When this happens, if magnet M is energized, as will normally be the case, the raising of the fulcrum block will rotate the lever 61 in a clockwise direction to a position in which the dog 60 is clear of the notches. The motion of the locking device 27 necessary to force the fulcrum block 70 to its upper position will, due to the proportioning of the parts pointed out hereinbefore, be insufficient to cause the dog 60 to move into engagement with the forward or left-hand end of the notch 62, and as soon as the dog has been withdrawn from the notch 62, the apparatus will then function in the same manner as would be the case if the auxiliary locking mechanism were not provided.

It should be noted that when magnet M becomes energized due to a train trailing the switch, the contact 80-81-82 will become

closed, and will thus provide a means for controlling a suitable signal at the switch. This signal will usually be so controlled that it will only be clear when the contact 80—81—82 is closed, and the locking plunger 27e as checked by the indication circuit controller E is in its proper locking position.

When it is desired to operate the switch by means of the hand-throw lever, the initial movement of the hand-throw lever will cause the pin 85 to engage the return bend 84a of the spring 84 and bend the spring upwardly until the locking device has been moved to the right far enough to cause the cam 68 to move out of engagement with the depressor 66, whereupon the energy stored in the spring 84 will rotate the lever 61 to a position in which the dog 60 is withdrawn, the notches 62, 64 and 65 thereby releasing the locking device. As soon as the locking device has become released, the apparatus will then function in the manner described hereinbefore.

Although I have herein shown and described only one form of railway switch operating apparatus embodying my invention, it is understood that various changes and modifications may be made therein within the scope of the appended claims without departing from the spirit and scope of my invention.

Having thus described my invention, what I claim is:

1. Switch operating mechanism comprising a reciprocable motion plate, means including a manually operable segment gear for reciprocating said motion plate, a locking plunger operably connected with said motion plate by means of springs and moved by said motion plate between two extreme positions corresponding to the extreme positions of said motion plate, auxiliary means for at times moving said locking plunger away from its one extreme position in opposition to the bias of said springs, said plunger being adapted when in its one extreme position to cooperate with means for locking the switch in its one extreme position, means actuated by said motion plate for moving the switch between its two extreme positions, a member secured to said locking plunger and provided with a notch and with a cam surface, a fulcrum block cooperating with said member and movable from a lowered to a raised position in response to movement of said plunger away from said one position, an electromagnet, a lever pivotally connected intermediate its ends to said fulcrum block and operatively connected at one end with the armature of said electromagnet, a locking dog pivotally connected to the other end of said lever and movable when said fulcrum block occupies its lowered position and said magnet is deenergized to a locking position in which it enters the notch in said member to prevent movement of said plunger to its other extreme position, a pivoted depressor cooperating at one end with said dog and at the other end with said cam and effective when said plunger occupies its one extreme position to force said dog into said notch, the parts being so proportioned that movement of said fulcrum block to its raised position when said magnet is energized will withdraw said dog from said notch, and means secured to said lever and cooperating with means secured to said segment gear for moving said lever to a position in which said dog is withdrawn from said notch when said gear is actuated in the direction to move said motion plate to its other extreme position.

2. The combination with a railway switch movable between normal and reverse positions and operating mechanism for said switch comprising a manually operable lever, means controlled by said lever for operating said switch, and a locking plunger which is biased to a locking position when said switch is moved by said lever to its normal position and is moved to an unlocking position prior to any movement of the switch 10 when said lever is operated to move said switch away from its normal position and which plunger cooperates in its locking position with means for locking the switch in its normal position, of a member secured to said locking plunger and 15 provided with a notch, a locking dog movable to a locking position in which it enters said notch when and only when said locking plunger occupies its locking position and biased by gravity to its locking position and effective when 20 in its locking position to prevent movement of said locking plunger away from its locking position, an electromagnet, means responsive to an initial movement of said locking plunger toward its unlocking position when said electromagnet 25 is energized for moving said locking dog to its unlocking position, and other means responsive to movement of said manually operable lever in the direction to move said switch to its reverse position for moving said locking dog to its 30 unlocking position.

3. The combination with a railway switch movable between normal and reverse positions and operating mechanism for said switch comprising a manually operable lever, means controlled by said lever for operating said switch, and a locking plunger which is biased to a locking position when said switch is moved by said lever to its normal position and is moved to an unlocking position prior to any movement of the switch 35 when said lever is operated to move said switch away from its normal position and which plunger cooperates in its locking position with means for locking the switch in its normal position, of a member secured to said locking plunger and provided with a notch and with a cam surface, a fulcrum block cooperating with said member and movable from a lowered to a raised position in response to movement of said plunger away from its locking position, an electromagnet, a second lever pivotally connected intermediate its ends to said fulcrum block and operatively connected at one end with the armature of said electromagnet, a locking dog pivotally connected to the other end of said second 40 lever and movable when said fulcrum block occupies its lowered position and said magnet is deenergized to a locking position in which it enters the notch in said member to prevent movement of said plunger to its unlocking position, a pivoted depressor cooperating at one end with said dog and at the other end with said cam and effective when said plunger occupies its locking position to force said dog into said notch, the parts being so proportioned that 45 movement of said fulcrum block to its raised position when said magnet is energized will withdraw said dog from said notch, and means secured to said second lever and cooperating with means operated by said manually operable lever for moving said second lever to a position in which said dog is withdrawn from said notch when said manually operable lever is actuated in the direction to move said switch to its reverse position.

4. The combination with a spring switch, a

locking plunger biased to a locking position and cooperating when in its locking position with means for locking the switch in its normal position, and means actuated by a train trailing said switch when it occupies its normal position for moving said locking plunger to its unlocking position, of a locking dog movable between a locking and an unlocking position and cooperating in its locking position with said locking plunger to prevent more than an initial movement of said locking plunger toward its unlock-

ing position, an electromagnet, and means controlled in part by said electromagnet and effective if and only if said electromagnet is energized for moving said locking dog to its unlocking position in response to an initial movement of said locking plunger toward its unlocking position to permit movement of said locking plunger to its full unlocking position by said train actuated means.

10

HERBERT L. BONE.
